UNITED STATES PATENT OFFICE.

FREDERICK W. BÖSCH, OF CAMDEN, NEW JERSEY, ASSIGNOR TO WORTHINGTON PUMP AND MACHINERY CORPORATION, OF NEW YORK, N. Y., A CORPORATION OF VIRGINIA.

STEAM-ENGINE.

1,401,866.

Specification of Letters Patent. Patented Dec. 27, 1921.

Application filed April 22, 1916, Serial No. 92,891. Renewed May 28, 1919. Serial No. 300,478.

To all whom it may concern:

Be it known that I, FREDERICK W. BÖSCH, a citizen of the United States, residing at Camden, in the county of Camden and State of New Jersey, have invented certain new and useful Improvements in Steam-Engines, of which the following is a specification.

My invention relates to improvements in steam engines of the construction generally designated as the uniflow type, and in which the live steam enters the cylinder at the ends thereof and the expanded steam is exhausted mainly through ports at or near the end of the stroke, distant from the admission port, said ports being uncovered by the piston at or near the end of its working stroke.

The objects of my invention are:

First, to construct an engine of the uniflow type as above indicated, in which all the advantages of said type are fully carried out without necessitating the use of an abnormally long cylinder and piston.

Second, to construct an engine of the uniflow type, in which the clearance and back pressure are reduced to a minimum and at the same time prevent the compression from exceeding the initial live steam pressure, thereby insuring the highest efficiency and economy at all speeds of the engine under all conditions, especially non-condensing.

Third, to construct an engine of the uniflow type in which the cylinder is provided with such an arrangement of admission and a plurality of exhaust ports and a single valve controlling at proper times all of said exhaust ports, so that it is possible to employ a shorter cylinder and piston, greater simplicity, less valve mechanism, and at the same time reduce the compression lower than has been used heretofore and produced in a uniflow engine of the same horse power.

Fourth, to construct an engine of the uniflow type in which the cylinder is provided with such an arrangement of live steam admission ports, and a plurality of expanded steam exhaust ports combined with valve mechanism controlling all of said exhaust ports, that the lower temperature of the expanded steam passing out of said exhaust ports will not be in proximity to and affect the high temperature of the live steam passing through the admission ports and into the cylinder.

55 Other advantages and objects of the in-

vention will appear from the detailed description of the construction and mode of operation of the invention to be presently disclosed.

My invention consists of structural characteristics and relative arrangement of elements which will be hereinafter more fully described and particularly pointed out in the appended claims.

In the accompanying three sheets of drawings similar reference characters indicate the same parts in the several figures in which:

Figure 1, is a longitudinal sectional view of the engine taken on line I—I of Fig. 2;

Fig. 2 represents one-half transverse sectional views of the engine, the view on the left side of the figure being a section taken on line II—II, while the view on the right side is a section taken on III—III of Fig. 1.

Figs. 3 to 12, inclusive, are diagrammatic views showing the different positions of the piston and ports of the single exhaust valve with respect to the cylinder exhaust ports, throughout one entire cycle of operation of the engine.

Fig. 13 is a longitudinal sectional view of the engine partly in side elevation showing the gear for properly operating the exhaust valve.

Referring to Figs. 1 and 2, 10 indicates a steam engine cylinder having the usual live steam admission ports 11 at the end of the cylinder controlled by admission or inlet valves 13 operated by any convenient form of valve gear, not shown. Poppet valves 13 are shown for controlling the admission of the live steam to the cylinder, but any other form of live steam distribution valves may be employed, without affecting the novel features of my invention and I contemplate using other forms of said valves, if so desired. It will also be understood that while I have shown valves 13 in connection with heads 14 and cylinder 10 provided with steam jackets to construct a steam jacketed or heated uniflow cylinder which is completely insulated, as illustrated, any other forms of heads and cylinders can be readily substituted therefor, or the valves may be within the cylinder casting without in any way modifying the construction and mode of operation of the essential features of my invention to be presently described. Said steam jackets of the cylinder 10 are ar-

110

ranged as shown so as to not only surround the cylindrical walls of the cylinder, but also the two cylinder ends, whereby the condensation of the steam in said cylinder is reduced to a minimum and the cylinder barrel is entirely insulated and uniformly heated in order to maintain its temperature equal to that of the incoming motive expansive fluid, which is most essential in an engine of the uniflow type.

Cylinder 10 is provided with the usual form of piston 15, connected with a rod 15', cross-head 15^a connecting rod 15^b, crank 15^c to a shaft 15^d, as shown in Fig. 13, or said piston rod 15' may be properly attached to any other form of transmission mechanism, depending on the form of motion desired to be transformed from the reciprocations of the piston to the valves.

20 Preferably at the lower side and middle section of the cylinder 10 is provided a central or auxiliary exhaust port 16 and on each side of said central or auxiliary exhaust port and between the ends of the cylinder is properly arranged a main exhaust port 17 or 18. All of said three exhaust ports 16, 17 and 18 are separated and independent of each other and lead to and communicate with a common and final exhaust opening 19, and each of said exhaust ports 16, 17, and 18 instead of being one continuous opening where it enters the cylinder, is preferably formed of a series of openings by providing a plurality of bridge sections 10', as shown in order to have a proper bearing for the lower portion of the piston over the exhaust valve and also prevent the packing rings of the piston from springing out. Uneven wear of the piston is avoided by the

40 staggered relations of the bridge sections 10' and cylinder openings of the ports 16, 17 and 18.

In the preferred construction shown, with a single exhaust chamber and a single exhaust-controlling valve between the cylinder ends of the three exhaust ports 16, 17 and 18, and the final exhaust opening 19, is interposed an enlarged chamber 20 preferably circular in cross-section as shown, in which is provided an oscillating exhaust controlling valve 21, having cored therein ports 22, 23, 24 and 25, communicating with each other, and port 22 adapted to register with the central exhaust port 16, port 23 regis- ters with exhaust port 17, port 24 with exhaust port 18, and port 25 constantly in communication with ports 22, 23 and 24 of the exhaust valve and the final or common exhaust opening 19. Said single exhaust valve 21 is preferably of the Corliss or oscillating type, but any other form of single valve may be employed which would be readily suggested by those skilled in the art of steam engine building. A stem or rod 26 is attached to the exhaust valve which may

be connected to any moving part of the engine to be properly operated as shown for example in Fig. 13, by means of the crank arm 26^a, link 26^b, rocker arm 26^c, eccentric rod 26^d, and eccentric 26^e rotated by crank 70 shaft 15^d in order that the proper ports of the exhaust valve 21 are correctly timed with respect to the cylinder exhaust ports 16, 17 and 18 and position of piston 15.

The different operations of the invention 75 throughout all its phases of movements showing the relations of the piston with the cylinder exhaust ports, and the exhaust valve ports with respect to said cylinder exhaust ports, are fully shown and will be clearly understood by following the motions of the piston and path of the exhaust steam indicated by the arrows in Figs. 3 to 12.

Fig. 3 shows the piston approaching end of stroke to the left and having begun to 85 uncover the cylinder exhaust port 18, with the exhaust valve 21 in such a position to permit the expanded steam to exhaust through port 18, valve ports 24 and 25 to the common exhaust opening 19. 90

In Fig. 4 the piston is at end of stroke to the left and about to receive live steam and begin stroke to the right with cylinder exhaust port 18 completely uncovered and expanded steam continuing to pass out port 95 18, through valve ports 24 and 25 and opening 19.

In Fig. 5, the piston has closed the cylinder exhaust port 18 and the exhaust valve 21 has assumed the position to permit the 100 expanded steam to exhaust through cylinder port 16 and valve ports 22 and 25 to opening 19.

In Fig. 6, the piston has uncovered port 18 and closed port 16 to the exhaust, and the 105 exhaust valve 21 has assumed such a position to close port 18 to the final exhaust opening 19 and permit the expanded steam to exhaust through port 17.

In Fig. 7, the piston has uncovered ports 110 18 and 16 and closed port 17 and all cylinder exhaust ports 16, 17 and 18 are cut off from the final exhaust opening ports 18 and 16 by the valve 21 and port 17 by the piston, and the remaining expanded steam trapped 115 between piston and cylinder head is properly compressed to insure the smooth running of the engine.

In Figs. 8, 9, 10, 11 and 12 the operations above indicated are the same as described 120 with reference to Figs. 3, 4, 5, 6 and 7, respectively, except that the piston and exhaust valve are moving in the opposite direction, and the expanded steam is exhausted mainly through the port 17, instead of port 125 18 as shown in Figs. 3 to 7.

From the foregoing disclosure of the operation of my invention, it will be seen that the cylinder exhaust ports 16, 17 and 18 are only opened one after another in uniflow 130

order, and the end or outer exhaust port 17 or 18 opened at the end of the stroke and not the central exhaust port 16 performs the function of the main exhaust port through 5 which the initial or primary exhaust takes place at the end of the stroke, and the other outer exhaust port 17, or 18, depending whether it is the stroke to the right or left, is an auxiliary and final exhaust port for 10 that particular stroke, so that the main or primary exhaust port for one stroke is an auxiliary and final exhaust port for the opposite stroke, whereby the remaining vapor or highly expanded steam is permitted to 15 escape and delay the compression until the piston 14 has cut off and closed the last mentioned end or final exhaust port 17 or 18, each of these ports 17, 18 thus forming a combined main or primary and final or 20 auxiliary exhaust port.

It will also be seen that a piston of normal size and length is employed by my form of uniflow engine and is one-third in length of the piston usually employed by former 25 constructions of uniflow engine, and consequently a cylinder utilizing my form of invention is capable of being one-third shorter than the usual form of uniflow engine for the same stroke.

30 While it is true that extra expansion chambers or clearances are connected with the cylinder during the expansion of the live steam when the piston uncovers the ports 16 and 18 as disclosed in Figs. 6, 7, 11 and 35 12, yet before this additional volume of the ports 16 and 18 is in communication with the cylinder volume, the live steam pressure and temperature of the same have decreased to such an extent that the detriment to the 40 expansive powers of the live steam becomes and is negligible compared with the important benefits herein pointed out.

From the foregoing disclosure as to the construction, mode of operation and advantages of my invention it will be readily seen that all the objects recited in my statement of invention are fully carried out, and while I have described and shown my preferred 50 form of invention, I am not limited to this specific form, as many changes and modifications will readily suggest themselves to any one skilled in steam engine building, and include within my invention all modifications of the same which do not depart 55 from the spirit of the invention as defined in the claims, and are so modified to suit a particular design or type of engine.

What I claim is:

1. A steam engine of the uniflow type 60 comprising a cylinder, a piston within the cylinder, a live steam inlet port at each end of the cylinder, means for controlling the admission of live steam through said live steam ports and to the opposite sides of the 65 piston, one intermediate and two distinct

and independent combined main and auxiliary exhaust ports at different and separated sections along the length of the cylinder, and a single valve controlling the three exhaust ports at each stroke of the 70 piston.

2. A steam engine of the uniflow type comprising a cylinder, a piston within the cylinder, a live steam inlet port at each end of the cylinder, means for controlling the 75 admission of live steam through said live steam ports and to the opposite sides of the piston, distinct and independent main, intermediate and final exhaust ports at different and separated sections along the intermediate 80 length of the cylinder, and a single four-ported valve controlling the main, intermediate and final exhaust ports at each stroke of the piston.

3. A steam engine of the uniflow type 85 comprising a cylinder, a piston within the cylinder, a live steam inlet port at each end of the cylinder, means for controlling the admission of live steam through said live steam ports and to the opposite sides of the 90 piston, an intermediate auxiliary exhaust port at the center section of the cylinder, a combined main and auxiliary exhaust port between the intermediate auxiliary exhaust port and each end of the cylinder, and an 95 oscillating and single four-ported valve controlling all of said exhaust ports at each stroke of the piston.

4. A steam engine of the uniflow type comprising a cylinder, a piston within the 100 cylinder, a live steam inlet port at each end of the cylinder, means for controlling the admission of live steam through said live steam ports and to the opposite sides of the piston, three distinct and independent exhaust ports at different and separate sections along the length of the cylinder and the outer ports next to the cylinder ends removed from said ends approximately the 105 length of the piston, and valve mechanism 110 controlling the three exhaust ports.

5. A steam engine of the uniflow type comprising a cylinder, a piston within the cylinder, a live steam inlet port at each end of the cylinder, means for controlling 115 the admission of live steam through said live steam ports and to the opposite sides of the piston, an auxiliary exhaust port at substantially the center section of the cylinder, a combined main and final exhaust 120 port between the auxiliary exhaust port and each end of the cylinder, and a single valve controlling the auxiliary exhaust port and the two combined main and final exhaust ports, said valve constructed, arranged and 125 operated whereby the main exhaust port of one stroke becomes an auxiliary exhaust port during the following stroke.

6. A steam engine of the uniflow type comprising a cylinder, a piston within the 130

- cylinder, a live steam inlet port at each end of the cylinder, means for controlling the admission of live steam through said live steam ports and to the opposite sides of the piston, an auxiliary exhaust port at substantially the center section of the cylinder, a main exhaust port between the auxiliary exhaust port and each end of the cylinder, and a single oscillating and ported valve controlling the auxiliary exhaust port and the two main exhaust ports, said valve constructed, arranged and operated whereby the main exhaust port of one stroke becomes an auxiliary exhaust port during the following stroke.
7. A steam engine of the uniflow type comprising a cylinder, a piston within the cylinder, a live steam inlet port at each end of the cylinder, means for controlling the admission of live steam through said live steam ports and to the opposite sides of the piston, a central auxiliary exhaust port at substantially the center section of the cylinder, a combined main and auxiliary exhaust port between the central auxiliary exhaust port and each end of the cylinder, and valve mechanism controlling the central auxiliary exhaust port and the two combined main and auxiliary exhaust ports.
8. A steam engine of the uniflow type comprising a cylinder, a piston within the cylinder, a live steam inlet port at each end of the cylinder, means for controlling the admission of live steam through said live steam ports and to the opposite sides of the piston, a central auxiliary exhaust port at substantially the center section of the cylinder, a combined main and auxiliary exhaust port between the central auxiliary exhaust port and each end of the cylinder, each of said combined main and auxiliary ports removed from the adjacent end of the cylinder approximately the length of the piston and valve mechanism controlling the central auxiliary exhaust port and the two combined main and auxiliary exhaust ports.
9. A steam engine comprising a cylinder having an intermediate port and a plurality of distinct and independent combined main and auxiliary exhaust ports along the length of the cylinder, a piston controlling the inlets of said exhaust ports and valve mechanism controlling the outlets of said exhaust ports.
10. A steam engine of the uniflow type comprising a cylinder having its cylindrical barrel and ends steam jacketed, a piston within the cylinder, a live steam inlet port at each end of the cylinder, means for controlling the admission of live steam through said live steam ports and to the opposite sides of the piston, three distinct and independent exhaust ports at different and separated sections along the intermediate length of the cylinder, the two outer exhaust ports being combined main and final exhaust ports and coöperating at each stroke of the piston, and valve mechanism controlling said three distinct and independent exhaust ports.
11. A steam engine of the uniflow type comprising a cylinder having its cylindrical barrel and ends steam jacketed, a piston within the cylinder, a live steam inlet port at each end of the cylinder, means for controlling the admission of live steam through said live steam ports and to the opposite sides of the piston, an auxiliary exhaust port at substantially the center section of the cylinder, a combined main and final exhaust port between the auxiliary exhaust port and each end of the cylinder, and valve mechanism controlling the auxiliary exhaust port and the two combined main and final exhaust ports, said valve constructed, arranged and operated whereby the main exhaust port of one stroke becomes an auxiliary exhaust port during the following stroke.
12. A steam engine comprising a cylinder of the uniflow type having a plurality of distinct and independent combined main and final exhaust ports and an auxiliary exhaust port interposed between said main and final exhaust ports so arranged and constructed as to enable the use of a short piston of normal length and construction, a piston within the cylinder controlling the inlets of all of said exhaust ports, and valve mechanism controlling the outlets of said exhaust ports.
13. A steam engine of the uniflow type comprising a cylinder having a plurality of combined main and auxiliary exhaust ports arranged to be covered and uncovered by the piston, in combination with a single valve controlling each of said ports to open one of the ports for primary exhaust after the piston has passed the port, and to close said port on the return stroke and open the other combined main and auxiliary exhaust port for final exhaust.
14. A steam engine of the uniflow type comprising a cylinder having a central exhaust port and a combined main and auxiliary exhaust port between said central port and each end of the cylinder arranged to be covered and uncovered by the piston, in combination with valve mechanism controlling each of said ports and acting to secure the primary exhaust of the cylinder through one of said combined main and auxiliary exhaust ports when the piston has passed said port and to open the central port and other combined main and auxiliary exhaust port on the return stroke of the piston for further exhaust.
15. A steam engine of the uniflow type comprising a cylinder having a central exhaust port and a combined main and auxiliary exhaust port between said central port and each end of the cylinder arranged to be

covered and uncovered by the piston, in combination with valve mechanism controlling each of said ports and acting to secure the primary exhaust of the cylinder through 5 one of said combined main and auxiliary exhaust ports when the piston has passed said port and further exhaust through the central port on the return stroke until the pis-

ton has passed said central port, and to open the other combined main and auxiliary port 10 for final exhaust through said port on the return stroke of the piston until the piston has passed said port.

In testimony whereof I affix my signature.

FREDERICK W. BÖSCH.
